UNITED STATES PATENT OFFICE.

JOHN W. MAILLOT, OF NORTH ATTLEBOROUGH, MASSACHUSETTS, ASSIGNOR
TO F. M. WHITING & CO., OF SAME PLACE.

DESIGN FOR A SPOON.

SPECIFICATION forming part of Design No. 22,916, dated November 28, 1893.

Application filed October 16, 1893. Serial No. 488,329. Term of patent 3½ years.

To all whom it may concern:

Be it known that I, JOHN W. MAILLOT, a citizen of the United States, residing at North Attleborough, Bristol county, Massachusetts, have invented a new and original Design for Spoons, of which the following is a specification.

The design is especially intended to provide a souvenir spoon for the State of California but is not limited in this respect.

The design is carried by the handle of the spoon and the accompanying drawing illustrates a face view of a spoon embodying my design.

The design is arranged to follow the outline of the handle spaces being left at 1, 2 to receive any desired inscription.

The design includes the representation of a bunch of fruit surmounting the head or upper end of the handle and of which grapes occupy the most prominent position. Along

the right and left sides or edges of the handle are arranged heads of wheat, these representing one of the products for which California is famous. Below this is a "horn of plenty" extending up lengthwise of the handle with its large open end or mouth directed toward the end of the handle. This horn is represented as overflowing with gold and silver. Below this again is a scroll D entwined with wheat extending to the lower end of the shank.

I claim—

The design for a spoon herein shown and described.

In testimony whereof I affix my signature in presence of two witnesses.

JOHN W. MAILLOT.

Witnesses:

WILLIAM H. POND,
ARTHUR T. PARKER.
